COLOSTOMY BELT

Pauline M. O'Meara, Bakersfield, Calif.

Application December 3, 1951, Serial No. 259,572

1 Claim. (Cl. 128—283)

1

This invention relates to new and useful improvements and structural refinements in colostomy belts, and the principal object of the invention is to provide a belt of the character herein described, which may be conveniently and effectively employed for sustaining surgical dressing in position while facilitating convenient inspection, cleansing and care of the affected area of the body.

Some of the advantages of the invention reside in its simplicity of construction, in the convenience and comfort of its use, and in its adaptability to economical manufacture.

With the above more important objects and features in view and such other objects and features as may become apparent as this specification proceeds, the invention consists essentially of the arrangement and construction of parts as illustrated in the accompanying drawings, in which:

Figure 1 is a perspective view of the invention per se;

Figure 2 is a front elevational view of the invention in use;

Figure 3 is a rear elevational view thereof;

Figure 4 is a side elevational view of the same; and

Figure 5 is a transverse sectional detail, taken substantially in the plane of the line 5—5 in Figure 1.

Like characters of reference are employed to designate like parts in the specification and throughout the several views.

Referring now to the accompanying drawings in detail, the invention consists of a colostomy belt which is designated generally by the reference character 10 and embodies in its construction an annular waist band 12 including a resiliently yieldable portion 14 and separable connecting means 16 of any conventional type, whereby the same may be conveniently installed around the waist.

A pair of straps 18 are secured at transversely spaced points to the front portion of the waist band 12 and extend downwardly therefrom in convergent relation, continuations of these straps constituting a pair of thigh engaging members 20.

A flexible panel 22 is secured at its upper edge to the front portion of the waist band 10 and overlies the downwardly extending portions of the straps 18, it being noted that the extremities

5 of the thigh engaging members 20 are connected to the opposite side edges of the panel 22 as indicated at 24. If desired, one or both of the thigh engaging members 20 may be provided with a resiliently yieldable portion 26 and separable connecting means 28 to facilitate donning of the belt.

10 A pair of strips 30 are secured at transversely spaced points to the rear portion of the waist band 12 and extend downwardly therefrom, their lower ends being connected at 32 to intermediate portions of the respective thigh engaging members 20, as will be clearly apparent.

15 Finally, in order to substantially stiffen the panel 22, suitable stays 34 may be embedded in portions of the straps 18 which are secured to the rear surface of the panel 22, as is clearly shown in Figure 5.

20 It is believed that the advantages and use of the invention will be clearly apparent from the foregoing disclosure and accordingly, further description thereof at this point is deemed unnecessary.

25 While in the foregoing there has been shown and described the preferred embodiment of this invention, it is understood that minor changes in the details of construction, combination and arrangement of parts may be resorted to without departing from the spirit and scope of the invention as claimed.

30 Having thus described the invention, what is claimed as new is:

35 A colostomy belt comprising an annular waist band including a resiliently yieldable portion and separable connecting means, a pair of straps having one end thereof secured at transversely spaced points to the front portion of said waist band and extending downwardly therefrom in convergent relation, continuations of said straps constituting a pair of thigh engaging members, a flexible panel 40 secured at its upper edge to the front portion of said waist band and overlying the downwardly extending portions of said straps, extremities of said thigh engaging members being connected to the respective side edges of said panel, and a pair of strips having one end thereof secured to the rear portion of said waist band at transversely spaced points and extending downwardly therefrom, lower ends of said strips being connected to intermediate portions of said members.

50 PAULINE M. O'MEARA.
